(57) **CLAIM**

The ornamental design for a vending kiosk, as shown and described.

DESCRIPTION

FIG. 1 is a front perspective view of a vending kiosk, showing my new design;

FIG. 2 is a rear perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof; and,

FIG. 8 is a bottom plan view thereof.

The broken line portion of the figure drawings is included to show portions of the article that forms no part of the claimed design.

1 Claim, 8 Drawing Sheets
